Patented Feb. 29, 1916.

UNITED STATES PATENT OFFICE.

JAMES F. ROWLEY, OF CHICAGO, ILLINOIS.

ARTIFICIAL HAND.

1,173,219.

Specification of Letters Patent. Patented Feb. 29, 1916.

Application filed December 27, 1915. Serial No. 68,882

To all whom it may concern:

Be it known that I, JAMES F. ROWLEY, a citizen of the United States of America, and a resident of Chicago, county of Cook, and State of Illinois, have invented certain new and useful Improvements in Artificial Hands, of which the following is a specification.

This invention relates mainly to artificial hands and more particularly to improvements in the structure of the thumb and two adjacent fingers and means for operating the thumb. Heretofore, provision for thumb movement has been limited substantially to 10 a hinge joint disposed intermediately of the length of the thumb with its pintle extending crosswise, whereby the movement of the thumb was similar to that of a human thumb having movement only at the second 15 joint connecting the metacarpal and first phalanx. Limited to such a joint it was impossible for the wearer to simulate the usual and natural action of the human hand as there could be no transverse movement 20 responding in any sense with that of the first metacarpal, and such prior movement being analogous to the movement of the human thumb at the outermost joint.

The main objects of this invention are to 25 provide an improved method of mounting and actuating the thumb in a manner adapted for simulating the natural action of the thumb in opening and closing the hand, particularly as to the movement of the 30 thumb as a whole with respect to the metacarpus or body of the hand; to provide an improved mounting and arrangement of the thumb and the two adjacent fingers in such manner as to facilitate gripping an article 35 thereby; to provide for resilient backward yielding of the forefinger in such manner as to accommodate articles of different thickness or size held between the thumb and the two fingers adjacent thereto; to provide improved means for locking the thumb in its 40 gripping position; to provide manual control means extending back from the thumb for attachment to the body of the wearer; to provide resilient restoring means adapted 45 for automatically retracting the thumb when it is released after having been swung forward by action of the wearer; and to provide a hand simulating the natural yielding character of the human hand and adapted 50 for shaking hands and for handling articles 55 in a life-like manner.

An illustrative embodiment of this invention is shown in the accompanying drawings, in which:

Figure 1 is a back view of the right arm, 60 hand and suspender as applied to the wearer, the latter being shown fragmentarily by dotted lines. Fig. 2 is a side view of the hand with the thumb swung forward against the two adjacent fingers, and holding a pencil. 65 Fig. 3 is a palm view of the hand also with the thumb swung forward, but with nothing held in the hand. Fig. 4 is a fragmentary view of the hand with the front part of the palm removed, showing the means whereby 70 the thumb is swung forward and retracted. Fig. 5 is an enlarged fragmentary longitudinal section through the little finger on the line A—A of Fig. 3. Fig. 6 is an enlarged fragmentary section on the line B—B of 75 Fig. 2. Fig. 7 is an enlarged fragmentary view on the line C—C of Fig. 4. Fig. 8 is a detail of the thumb lock plunger.

In the construction shown in the drawings, the artificial member as a whole comprises a hollow forearm 1 having therein a socket adapted to receive the stump of the wearer's forearm. A hand member 2 is mounted on said forearm member in any desired manner, preferably by a joint of ball 80 and socket nature, adapted to permit some degree of swinging and turning of the hand with respect to the forearm part, as will be understood. Means 3 are provided for gripping the wearer's upper arm 4, said means 85 comprising a frame 5 hinged at 6 to the forearm member 1 in such manner as to provide for elbow action, and also including a wide band 7 embracing the arm, straps and buckles being provided thereon as at 90 3.1 to facilitate adjustable attachment to the wearer.

Means for operating the hand are provided in the form of a suspender or harness-like structure 8 responsive to movements of 100 the body, said means being disposed across the back of the wearer and being adapted for adjustment as at 8.1 to fit the shoulders as at 9 and 10 and connected to the band 7 by the means 12 for giving support to the 105 device as a whole, said suspender also having flexible means 14 and 15 extending down to the hand, for actuating the thumb by movement of the shoulders, as hereinafter more fully described. The cord 14 coacts 110 directly with the hand, and the supporting loop 15 on which the upper end of said cord

is slidably carried is held slidably in the guides 16 on the part 1, and is secured adjustably to the suspender proper at 17.

The hand member 2 comprises a metacarpus or body part 19, having thereon the thumb 21 and the four fingers 22, 23, 24, and 25. The middle finger 23 and ring-finger 24 are rigid with the metacarpus 19, but the index finger 22 and little finger 25 are hinged at the base on pintles 27 and 29 respectively and are provided with resilient means 31 urging them forward. All of said fingers are curved or crooked somewhat and are disposed normally in a partly closed position with respect to the metacarpus, said index finger and little finger being swingable backward so that the hand may open somewhat.

The thumb member 21 is swingably mounted at its base on a hinge pintle 35, the axis of which is disposed lengthwise of the hand and substantially in alinement with the index finger when the latter is swung back to its open position. The thumb as a whole is inclined somewhat with respect to its said pintle 35, and comprises a hub-like base part 37 coaxial with said pintle and a body part 39 and 40 corresponding with the two phalanges of the human thumb. Said thumb member is crooked about forty-five degrees at the point 43 corresponding with the middle joint of the natural thumb where the thumb metacarpal and first phalanx meet, so that the outer or body part is disposed at an angle of about forty-five degrees to the hand. The thumb and fingers thus formed and arranged are so disposed that when the thumb is swung forward against the fingers, the inner side of the tip of the thumb first strikes diagonally against the outer part of the index finger 22, and thereby pushes it back, permitting the thumb to slide across said finger and come to rest against the side of the outer part of the middle finger 23. More specifically the pulp of the thumb strikes and slides across the pulp of the forefinger and comes to rest partly against the forefinger and partly against the side of the middle finger. In other words the thumb rotates into and out of contact with the fingers.

The thumb is swung forward by a pull on the cord 14, the lower end of which is attached to the thumb adjacent to the base or hub part 37. In order that said cord may pull with substantially uniform turning effect for all positions of the thumb, the inner side of the hub, corresponding with the ball of the thumb, is grooved peripherally as in a pulley sheave, to receive the coacting part of said cord. The cord groove 45 so provided is nearly as deep as the cord is thick and extends through an arc of about forty-five degrees corresponding substantially with the amplitude of thumb move-

ment. The outer part of said groove is in contiguous alinement with a perforation 47 extending through the thumb, in which the cord 14 is anchored by the set screw 48 which is accessibly disposed in the opposite side 70 of the thumb, where it may easily be concealed by plugging the hole as will be understood. Said cord 14 is disposed crosswise of the hand inside of and concealed normally by the palm. A large section 50 of the 75 palm is made removable, as understood in the art, so as to give access to the interior of the hand, said part 50 preferably being slidable edgewise away from the thumb for removal. Guide means are provided therefor including a pair of rollers or pulleys 51 and 52, one of which, adjacent to the thumb and opposite the groove 45, is disposed with its axis extending lengthwise of the hand, the other being positioned somewhat farther back toward the wrist and adjacent to the back edge of the hand and with its axis disposed perpendicularly to the palm. Adjacent to and back of the guide 52 is an aperture 55 through which the cord 90 14 enters the hand, said aperture being in the back or edge of the hand adjacent to the wrist.

Resilient means are provided for opposing the forward swing of the thumb and for 95 restoring it to its open position, said means comprising a helical spring 61 mounted in a cylindrical casing 62, closed at one end and open at the other. One end of spring 61 bears against the closed end 63 of the casing, and the other end coacts with a rod or link 65, one end of which projects into the open end of said casing. Said restoring means as a whole is connected at its ends to the thumb and metacarpus respectively, the outer end of the link 65 being connected turnably to the thumb at 69 and the closed end of the casing being turnably connected or seated at 70 adjacent to its outer end, at the back edge of the hand as shown in Fig. 7. 110

In order to enable the wearer to set or fix the thumb either in its wholly closed position or in any one of several intermediate positions, locking means are provided including a latch in the form of a bolt or plunger 73 mounted slidably on the hand adjacent to the wrist and opposite the adjacent end of the hub 37. Said end of the hub is provided with a series of apertures or sockets 75, 76 and 77 arranged in an arc 120 concentrically with the thumb pintle 35 for coacting with the plunger 73, which has a small forwardly projecting stud 79 adapted to fit in each of said apertures. Said plunger is slotted longitudinally at 81 for coaction with the fixed guide screws 82 whereby it is attached to the hand and is also provided with a handle part 85 to facilitate direct operation by the wearer with the other hand. A wear plate 87 is provided on 130

the lock end of said hub and said sockets are formed therein, the order recited being that in which they are brought into registry with the plunger 73 as the thumb is swung forward.

The mounting of the thumb 21 for swinging bodily as a whole, and the method of operation are closely analogous to the corresponding features in the human hand. The 10 thumb as a whole turns on a joint adjacent to the wrist corresponding with the joint at the base of the thumb where the first metacarpal is joined to the adjacent wrist bone or trapezium. The cord 14 corresponds substantially in position and effect with the 15 thumb closing muscle or adductor pollicis, which swings the thumb as a whole forward on the trapezium joint, toward the fingers. The restoring spring 61 corresponds in effect with the adductor muscle 20 which swings the thumb back as a whole away from the fingers. In order to accommodate the swinging movement of the thumb restoring members 65 and 62 respectively, the thumb base 37 and metacarpus 19 25 are apertured or slotted at 90 and 91 respectively, as shown in Figs. 4 and 7. In order that the thumb and pivoted finger members may present a most natural appearance and 30 operate in a most natural manner, their bases are rounded concentrically with their hinged pintles and the sockets therefor in the metacarpus are correspondingly rounded so as to present a substantially smooth and 35 continuous surface of the hand for all positions of the thumb and fingers.

The hand herein described is mechanically distinguished from the prior devices most conspicuously in that the path or locus of 40 the thumb is substantially like or similar to a segment of the frustum of a cone rather than flat or planar in character.

The operation of the embodiment shown as a whole is as follows: The artificial arm 45 is attached to the wearer and is adjusted by the several means provided therefor, the suspender attached to the shoulders being suitably adjusted, with respect to the tension, across the back so as to facilitate varying the tension on the thumb operating 50 cord at the will of the wearer by relative movement of the shoulders. By throwing one or both of the shoulders back the tension on the suspender is relaxed. This releases 55 the tension on the thumb closing cord and permits the restoring spring to throw the thumb back. In order to swing the thumb forward or close it against the fingers, the wearer throws one or both of the shoulders 60 forward somewhat so as to increase the tension on the suspender across the back and thereby pull upward more or less on the thumb cord sufficiently to swing the thumb forward to the extent desired. By this 65 means the wearer is enabled to grasp and

pick up most of the articles one may wish to use, as for example to handle a newspaper, to remove one's hat, to hold a pencil for writing, to hold a garden hoe, to shake hands, and to perform many other operations as will be understood. When a suitable glove is worn, the hand described is scarcely distinguishable by casual observation from a natural hand, even when performing its various functions.

Although but one specific embodiment of this invention is herein shown and described, it will be understood that numerous details of the construction shown may be altered or omitted without departing from the spirit 70 of this invention as defined by the following claims.

I claim:

1. An artificial hand, comprising a metacarpus or body part in combination with a 85 thumb member hinged thereto on an axis disposed lengthwise of the hand.

2. An artificial hand in which the forefinger and thumb are hinged on nonparallel axes to the metacarpus, the middle finger 90 being rigid thereon, resilient means urging said index finger forward, and means for urging said thumb forward into prehensile relation with said fingers.

3. An artificial hand in which the forefinger and thumb are hinged on nonparallel axes to the metacarpus, the middle finger being rigid thereon, resilient means urging said index finger forward, means for urging 95 said thumb forward into prehensile relation 100 with said fingers, and means for locking said thumb in its forward position.

4. An artificial hand, comprising a metacarpus or body part and one or more finger members thereon, in combination with a bent thumb member hinged thereto on an axis disposed lengthwise of the hand, and means for swinging said thumb member forward against said finger member or members.

5. An artificial hand in which the forefinger and thumb are hinged on nonparallel axes to the metacarpus, the middle finger being substantially rigid thereon and said fingers being normally in a partly closed position, said index finger being held forward yieldingly in said position and said thumb when swung forward coacting slidably with said index finger crosswise thereof and bearing against said middle finger, whereby said 115 hand is prehensile.

6. An artificial hand in which the forefinger and thumb are swingable on nonparallel axes, the middle finger being rigid on the metacarpus and said fingers being normally 120 in a partly closed position, means urging said index finger forward yieldingly to said position, and said thumb being swingable forward crosswise of and in sliding relation to said index finger sufficiently to bear 130

- against said middle finger, and said index finger being forced backward somewhat thereby.
7. An artificial hand, comprising a body part, in combination with a forefinger and a little finger mounted swingably thereon, resilient means urging said fingers forward, one or more finger members mounted substantially rigidly between said forefinger and little finger, a thumb member mounted swingably on an axis disposed lengthwise of the hand, and means adapted for extending back along the arm of the wearer for swinging said thumb member forward.
8. An artificial hand in which the fingers are normally in a semi-closed position, the two medial fingers being rigidly mounted and the adjacent fingers being hinged at their base, the thumb also being hinged at its base for swinging forward slidably past the index finger and against the finger adjacent thereto, yielding means urging said hinged fingers to their semi-closed position, and means manually controllable at will for operating said thumb.
9. An artificial hand, comprising a body member, an index finger hinged thereto, a rigidly mounted finger adjacent to the index finger, a crooked thumb hinged to said body member, the hinge axes of said index finger and thumb being substantially perpendicular to each other, resilient means urging said index finger forward, resilient means urging said thumb backward, flexible means extending backward from said hand for urging said thumb forward against said fingers, and means for locking said thumb in its forward position.
10. An artificial hand, comprising a metacarpus or body part in combination with a thumb member mounted swingably thereon, means for swinging said thumb member forward, resilient restoring means therefor, and a lock adapted for securing said thumb member in a forward position.
11. An artificial hand, comprising a metacarpus or body part in combination with a thumb member mounted swingably thereon, means for swinging said thumb member forward, resilient restoring means therefor, and a lock adapted for securing said thumb member in a forward position, said lock including a plunger mounted slidably on the metacarpus for advancing into engagement with the thumb, the latter being formed for engagement with said plunger.
12. An artificial hand, comprising a metacarpus in combination with a thumb member hinged thereon, the hinge axis being disposed longitudinally of the hand, one of said members having a plunger thereon and the other being formed for engagement with said plunger for locking the thumb in a fixed position relative to the metacarpus.
13. An artificial arm and hand adapted for securing to the wearer, in combination with a suspender disposed across the back and fitting the shoulders, and operating means extending from said suspender downward to the hand, said hand including a thumb mounted swingably on an axis parallel with the hand, said operating means being connected to said thumb for operating the same.
14. An artificial hand, comprising a metacarpus having a chamber therein, a thumb member mounted swingably on an axis disposed parallel to the hand at one side of said chamber, guide means in said chamber, and a cord leading downward to said hand and into said chamber, said cord passing through said guide means and being attached to the thumb for operating the same.
15. An artificial hand, comprising a metacarpus having a chamber therein, a thumb member swingable at its base on an axis parallel with the hand substantially in alignment with the base of the first finger, guide means in said chamber, an operating cord extending down to said hand and into said chamber, said cord being connected to said thumb and passing through said guide means, and resilient restoring means disposed in said chamber for opposing the action of said cord and adapted to restore the thumb after actuation by said cord.
16. An artificial hand, comprising a metacarpus having finger members thereon, in combination with a thumb member swingable against the fingers and hinged at its base on an axis disposed in the body of the metacarpus substantially in alignment with the base of the forefinger, tension and compression means attached to the ball of the thumb for swinging the thumb forward and backward respectively, and means for actuating one of said means at the will of the wearer.

Signed at Chicago this 22nd day of Dec., 1915.

JAMES F. ROWLEY.
